United States Patent Office.

GEORGE WEBB, OF LEWISTON, MAINE.

Letters Patent No. 73,853, dated January 28, 1868.

IMPROVED BRIDLE-BIT.

The Schedule referred to in these Letters Patent and making part of the same.

TO ALL PERSONS TO WHOM THESE PRESENTS SHALL COME:

Be it known that I, GEORGE WEBB, of Lewiston, in the county of Androscoggin, and State of Maine, have invented a new and useful Improvement in Bits for Bridles of Harnesses; and I do hereby declare the same to be fully described in the following specification, and represented in the accompanying drawings, of which—

Figure 1 is a top view,

Figure 2 an end elevation, and

Figure 3 a horizontal section of a bit provided with my invention.

In the drawings, A denotes a common bar-bit, of which *a* is the bar, and *b b* the two rings, the latter being fastened to the ends of the bar, and extended therefrom, in manner as represented. Between the two rings, and on the bar, so as to turn freely thereon, are two hangers, C C, each being provided with an eye, *f*, going through its upper part, and also with an arm, *g*, extended downward from it, and furnished with an eye, *a*, arranged as shown in fig. 2. Each of the bit-hangers has the shape of a wheel, but it may be a disk, either plain or embossed, or otherwise ornamented. These bit-hangers are for supporting the bit, by means of the plain or embossed, or otherwise ornamented. These bit-hangers are for supporting the bit, by means of the headstall side straps, which are buckled into the eyes *f f* of the two hangers. They allow the bit, when in the mouth of a horse, to turn freely therein, when pulled on by the driving-rein, without throwing the side straps of the headstall into an awkward position, as is apt to be the case when the straps of the headstall are buckled into the rings of the bit. Furthermore, the eyes of the arms *g g* serve to connect the bit with the standing martingale, so that the latter shall be independent of the driving-rein rings *b b*. The arms also answer for attaching the curb-rein to the bit, the curb being, by means of the hangers, operated without effecting any strain on the driving-rein, running from the rings *b b*.

The advantage of this bit is that it may be worn with greater ease and comfort for the horse than a common bar or curb-bit. With it, he is not likely to throw his head up or down, as often he will when a common snaffle or bar-bit is used in his mouth. With the improved bit, the headstall-straps are not liable to be drawn away by the driving-rein, as they are with a common bit, and even when they are buckled into its rings or eyes.

I make no claim to the invention or bit described and claimed in the United States Patent, No. 40,312, dated October 13, 1863, in which the curb-rein or hitching-levers B B revolve or turn freely on the journals of the bit-roller A, and are separate from the headstall-hangers D D, whereas, in my improved bit, each of the curb-rein hitching-arms *g*, and the headstall-hangers C C, is in one piece or lever, free to revolve on the bit-bar *a*, whose rein-hitching eyes *b b*, are fastened directly to its ends.

I claim, therefore, my improved bit, as made, with each of its headstall-hangers C, and its martingale or curb-rein hitching-arm *g*, in one piece, to revolve on the cross-bar *a*, provided with rein-rings or eyes, *b b*, as specified.

GEORGE WEBB.
